WATERBORNE VEHICLE

George O. Kulbe, 2720 Heatter Ave.,
Spring Lake, N.C. 28390

Filed Aug. 8, 1969, Ser. No. 18,589

Term of patent 14 years

Int. Cl. D12—06

U.S. Cl. D71—1

FIG. 1 is a side elevational view of a waterborne vehicle showing my new design.

FIG. 2 is a side elevational view rotated ninety degrees relative to FIG. 1.

FIG. 3 is a top plan view of FIG. 1.

FIG. 4 is a bottom plan view of FIG. 1.

I claim:

The ornamental design for a waterborne vehicle, as shown.
